UNITED STATES PATENT OFFICE.

JAMES MILTON WAUGH, OF CHICAGO, ILLINOIS.

CAR CONSTRUCTION.

1,186,461.

Specification of Letters Patent. Patented June 6, 1916.

Application filed August 10, 1914. Serial No. 856,005.

To all whom it may concern:

Be it known that I, JAMES MILTON WAUGH, a citizen of the United States, and a resident of the city of Chicago, in the county of Cook and State of Illinois, have invented certain new and useful Improvements in Car Construction, and I do hereby declare that the following is a full, clear, and exact description of the same, reference 10 being had to the accompanying drawings, and to the numerals of reference marked thereon, which form a part of this specification.

This invention relates to an improved 15 type of car construction adaptable to all kinds of cars, both passenger and freight.

Although the usual draft and buffing gears mounted on the car underframes serve to obviate to a great extent the otherwise 20 disastrous effects of the lesser buffing stresses, still this protection is mainly useful in protecting the underframe. In loaded cars there is a tendency to rack and injure the car body, due to the inertia of the 25 contents of the car exerted upon the walls of the car, and also due to the inertia of the car body itself. The stresses so produced in heavy buffing are sometimes so extreme as to cause the car body to tear loose, or partly 30 tear loose, from the underframing. The general tendency in recent years has been to build stronger and much heavier bodies and underframes in an attempt to withstand 35 these inertia stresses, thus aggravating the difficulty rather than obviating the same.

In the present invention the car body is yieldably mounted upon the under frame and the connections therebetween are effected through the medium of a number 40 of buffing riggings disposed upon the under frame and the body at the ends and intermediate the ends of the car body and engaged suitably with the car body so that shock transmitted to the car body from the 45 underframe is evenly distributed to, and is absorbed by said buffing or shock absorbing gears.

It is an object of this invention to provide 50 a car construction wherein a car body is yieldably mounted upon its underframe with a series of coating buffing or shock absorbing devices disposed upon the car body and underframe to absorb the stresses tending to produce a relative movement 55 therebetween.

It is also an object of this invention to

construct a car provided with a car body movably mounted upon the underframe having the usual draft and buffing gears and also equipped with independent shock absorbing gears mounted on the frame and the car body and extending across each end of the car, and also, if desired, with shock absorbing devices between the center sills of the underframe and intermediate the ends thereof, and operatively connected with the car body to absorb stresses exerted between the car body and the underframe.

It is also an object of this invention to construct a car wherein a plurality of shock absorbing mechanisms are mounted above the buffer blocks at each end of the car and coact with suitable abutments secured upon the car body, which is yieldably mounted upon the car frame, to absorb stresses exerted between the car body and the car frame.

It is furthermore an object of this invention to construct an improved form of box car in which the car body is provided with a suitable floor frame and is mounted upon and movable longitudinally of an underframe, said frames being operatively connected in part through the medium of shock absorbing devices mounted on both 85 frames to yieldingly resist movement of the car body relative to the underframe.

It is finally an object of this invention to provide an improved form of car construction acting to obviate the battering effect of 90 the contents of a car upon the car body by mounting the car body movably and yieldably upon the underframe and providing means to yieldingly resist such movement.

The invention (in a preferred form) is 95 illustrated in the drawings and hereinafter more fully described.

In the drawings: Figure 1 is a conventional side elevation of a box car embodying the principles of my invention. Fig. 2 is a top plan view of the car with the body removed. Fig. 3 is an enlarged, fragmentary section taken on line 3—3 of Fig. 2, and with parts shown in elevation. Fig. 4 is an enlarged, fragmentary detail section taken 100 on line 4—4 of Fig. 3. Fig. 5 is an enlarged, fragmentary detail section taken on line 5—5 of Fig. 2. Fig. 6 is a fragmentary detail section taken on line 6—6 of Fig. 5. Fig. 7 is an enlarged, fragmentary detail 110 section taken on line 7—7 of Fig. 5. Fig. 8 is a fragmentary detail section taken on

line 8—8 of Fig. 3. Fig. 9 is an enlarged detail view taken on line 9—9 of Fig. 2. Fig. 10 is an enlarged detail view of one end of a car in section, of a modified form 5 of my invention. Fig. 11 is an enlarged detail section on line 11—11 of Fig. 10. Fig. 12 is an enlarged detail section on line 12—12 of Fig. 10.

As shown in the drawings: The adaptation of my invention is not necessarily limited to any particular type of car construction, and accordingly for the purpose of description I have only illustrated such details sufficient to show only one construction of a number of possible variations. A pair of horizontal channel members 1 and 2, affording center sills of the underframe, are disposed parallel to and faced oppositely from one another back to back, as clearly 20 shown in Fig. 5. The side sills of the underframe comprise inwardly facing channel members 3 and 4, respectively, and may be connected in any suitable manner to said center sills 1 and 2, both at the ends and 25 intermediate the ends of the underframing, as usual or as desired, but the details of which are not entered into here.

The car body, in the present instance shown as a box car, is denoted as a whole 30 by the reference numeral 5, and is provided with a bottom frame, on which the flooring 6, is secured, and which in the construction shown consists of angle bars 7, forming the car side sills, which face inwardly and are 35 disposed on each side of the car and extending longitudinally thereof. The flanges of said bottom or car side sills 7, rest slidably on the side sills of the underframe and the webs of the same extend downwardly at 40 the outer side of each of said side sills and are approximately the same width as said side sills and fit closely thereto. Car bottom center sills 12, as shown in Fig. 5, slidably rest on each of the center sills 1 and 2, 45 of the underframe and are shown as downwardly facing channel bars, the outer downturned flange 12^a, of each of which engages over and extends below the outwardly directed top flange of the corresponding center sill 1 or 2. Transverse bars 8 (any desired number of which may be used) rigidly connect said car bottom, side and center sills and any desired number of transverse 50 truss bars 9, are provided at the ends of the car and intermediate the ends of the car, which fit closely beneath the center sills 1 and 2 and side sills 4 of the underframe and 55 at their ends are turned upwardly and rigidly secured to the outer faces of the respective car bottom side sills 7, so that said car bottom frame may slide longitudinally of the underframe.

A buffer block 10, is provided at each end 60 of the underframe as usual, and mounted on 65 and secured to each end of the underframe

and to the car bottom frame above said buffer blocks are a series of transversely arranged shock absorption or buffing devices. In the construction illustrated in the drawings, said shock absorption devices comprise 70 a plurality of transversely arranged gear casings 11, rigidly secured on each end of the underframe and facing toward the car body, as shown in Fig. 8, and, if preferred, constructed of cast steel, a single cast member affording any desired number of gear casings, and a like number of abutment heads 13, are rigidly secured on each end of the car bottom frame to extend into said casings 11. Said abutment heads may be secured in any suitable manner to the car bottom frame. As shown, however, the end of each of the car bottom side sills 7, and the car bottom center sills 12, is struck upwardly and fits over a horizontal flange portion 13^a, of abutment members 13, and rivets or bolts extending through said car bottom sills 7 and 12, rigidly connect the same together. Said abutments are preferably constructed of cast steel and integrally constructed as before described, with reference to the casing members, and preferably said member when so made, is recessed at the rear side to fit to the car end, the bottom flange 13^a, extending therebeneath, and end flanges 13^b, extending along the side of the car and secured thereto. Said abutment members interfit with the respective casings 11, at each end of the car underframe and positioned within each of said casings are 85 a series of resilient flat friction plates 14, arranged in a group or groups, and if more than one group in each casing, then spacing members 15, are positioned between the respective groups, so that when said abutments 13, are thrust into the casing by movement of the car body on the underframe, the plates in groups are caused to bend, as well as slide inwardly a slight amount into the casing.

Casings 16, open at their ends and on the upper side thereof, are rigidly secured between said respective center sills 1 and 2, at points intermediate the ends thereof, and slidably placed therein are groups of resilient friction plates 17, such as before described and similarly arranged, each of said groups having interposed therebetween spacing members 18, which permit curvature of the groups of plates when the same are 115 stressed. Also rigidly secured to said respective center sills 1 and 2, are stops or rigid shoulders 19, which contact the ends of the casing 16, and project inwardly beyond the walls thereof into a position to 120 hold follower blocks 20, within the casing, with the inner curved walls thereof contacting the adjacent group of friction plates.

Angle iron guides 21, are rigidly secured on each of the side walls of the casing 16, 130

and engage over the upper edges of the respective plates 17, and blocks 18 and 20, to hold the same slidably within the casing and prevent displacement thereof. A pair of 5 downwardly projecting abutment members 22, are rigidly secured on the under side of each of the car bottom center sills 12, in a position to engage against each of the respective follower blocks 20, so that when 10 relative movement takes place between the car body and the underframe, one of the follower blocks 20, is moved inwardly, thus stressing the groups of plates against corresponding follower block at the opposite end 15 the particular absorption gear, which is held from movement by its stops or shoulders 19.

In the modified form of my invention illustrated in Figs. 10, 11 and 12, I have 20 illustrated the casings of the absorption gear formed integral with one another in four sections by the reference numeral 23, and have shown the same attached on the front end of the car body 24, and instead of the 25 usual traveling follower blocks I have formed a long one-piece stationary abutment 25, grooved to form abutments one for each section of the draft gear casing and rigidly bolted upon the end of the underframe above 30 the buffer block 26, of the car frame.

The operation is as follows: The normal position of the car body 5, upon the car underframe is that with the body centralized or positioned equi-distantly between the 35 respective ends of the underframe with the various groups of plates in the draft rigging both at the ends of the car and intermediate the ends thereof normally stressed to an extent to insure immediate action of the gear upon impact. In the event of a shock being 40 transmitted to the car, as in buffing or coupling, or even due to relative changes of speed, the inertia of the contents, which would otherwise tend to batter out the ends 45 of the car, is yieldably absorbed in the various draft riggings which are disposed at various points in order to effect an even distribution of the shock thereto.

The action of the individual shock absorbing 50 gears is well known, that is, the impact transmitted thereto causes a curvature of the plates stressing them out of their normal plane, the resistance being vastly augmented by the face friction of the plates against 55 each other. The recoil is absorbed by the friction between the respective plates.

In the modified form of my invention illustrated in Figs. 10, 11 and 12, I have merely interchanged the end absorption 60 gearing members, securing the casing upon the car body and the abutment heads which interfit therewith rigidly bolted upon the end of the underframe. It is obvious that 65 the operation of this form is exactly similar to that already described, but under certain

conditions of operation this type of my invention is better adapted for the use or particular purpose to which certain cars are put.

It is obvious that the disposition of the various absorption gears may be varied 70 through a wide extent, and in fact depends largely upon the particular construction of the cars to which the device is adapted. However, I do not purpose limiting the patent granted otherwise than necessitated 75 by the prior art.

I claim as my invention:

1. A car underframe embracing longitudinally extending center sills, side sills rigidly secured thereto, a car body movably mounted upon said center and side sills, angle irons secured to said car body engaging over the outer surfaces of the side sills, means extending beneath said side and center sills of the underframe and rigidly secured to the car body to retain the same on the underframe, and a plurality of shock absorbing means associated with said underframe adapted to absorb stresses between the car body and said car underframe. 90

2. In a device of the class described an underframe embracing side and center sills, a car body movably mounted thereon, means rigidly secured to the car body and extending beneath the side and center sills of the underframe to hold the car body thereon, and shock absorbing means connected on the underframe and body adapted to absorb stresses between the car body and the underframe. 95

3. In a device of the class described the combination with a car underframe embracing side and center sills of a body frame movably mounted thereon, a car body supported thereon, means secured to said body 105 frame extending beneath said side and center sills to hold the body frame thereon, shock absorbing gears disposed between the center sills of the underframe intermediate the ends thereof beneath the car body, and shock absorbing gears connected at the end 110 of the under frame and co-acting with said intermediate gears to absorb stresses between the car body and the underframe.

4. In a device of the class described a car 115 underframe embracing center sills, buffer blocks rigidly secured on the end thereof, shock absorbing means secured intermediate said center sills between the ends of the car frame, buffing gears attached to the car underframe and mounted above said buffer blocks, and a car body movably mounted upon said underframe, and connected with said absorption means and buffing gears whereby movement of the car body on the 120 underframe is resisted. 125

5. In a device of the class described a car underframe, a car body frame movably mounted thereon, a car body supported thereon, means secured on the body frame 130

- and engaging around and beneath the car under frame to hold the body frame associated with the under frame, and shock absorbing devices associated with said frames adapted to resist movement of the car body relative the underframe.
6. In a device of the class described a car underframe, buffer blocks forming a part thereof, a plurality of buffing gears connected to said underframe and mounted above the buffer blocks, a car body frame movably mounted upon the underframe, and means associated with the car body frame adapted to co-act with the respective buffing gears to resist movement of the car body frame on the under frame.
7. In a device of the class described a car underframe, buffer blocks associated therewith, buffing gears mounted above said buffer blocks on each end of the car frame, a car body frame movably mounted upon the under frame, mechanism associated with the body frame to coact with the buffing gears on the underframe to resist movement of the body frame relative the underframe; and means rigidly secured to the car body frame and engaging beneath the car underframe to hold the two associated with one another.
8. In a device of the class described a car body adjustably mounted on a car underframe, shock absorbing devices mounted transversely across the car body above the buffer blocks at each end of the car underframe to resist movement of the car body on said underframe, and means secured to said car body and engaging transversely below said underframe to permit adjustment between said car body and underframe.
9. A device of the class described embracing a car underframe, a car body mounted thereon, shock absorbing devices mounted between said car body and car

frame, and means secured to the car body and engaging transversely beneath the car underframe permitting adjustment of said car body on said car underframe.

10. In a device of the class described a car underframe, a car body frame adjustably mounted thereon, a car body supported on said body frame, single acting shock absorbing means connected at the ends of said frames, and double acting shock absorbing means secured to said frames at points intermediate the ends thereof, said shock absorbing means adapted to resist movement between said frames.

11. In a device of the class described a car underframe, a car body frame movably mounted thereon, a car body supported thereon, means secured on the body frame and engaging around and beneath the car underframe to hold the body frame associated with the underframe, and a plurality of groups of single and double acting shock absorbing devices respectively secured to the ends and intermediate the ends of said frames adapted to resist movement of the car body relative the underframe.

12. In a device of the class described a car underframe, a car body mounted thereon, single acting shock absorbing means secured to the ends of said underframe and car body, and double acting shock absorbing means secured to said underframe and body at points intermediate the ends thereof, said shock absorbing means adapted to resist movement of the car body on said underframe.

In testimony whereof I have hereunto subscribed my name in the presence of two subscribing witnesses.

JAMES MILTON WAUGH.
